(74) **Attorney, Agent, or Firm:** Hewlett Packard Enterprise Patent Department

(57) **CLAIM**

We claim the ornamental design for an enclosure, as shown and described.

DESCRIPTION

FIG. 1 is a top right perspective view of an enclosure; FIG. 2 is a top left perspective view thereof; FIG. 3 is a front view thereof; FIG. 4 is a rear view thereof; FIG. 5 is a left side view thereof; FIG. 6 is a right side view thereof; FIG. 7 is a top thereof; FIG. 8 is a bottom view thereof; FIG. 9 is an enlarged right perspective view of the enclosure of FIG. 1 taken along line 9-9; FIG. 10 is an enlarged left perspective view of the enclosure of FIG. 1 taken along line 10-10; and, FIG. 11 is a front view of the enclosure of FIG. 1 taken along line 9-9.

The ornamental design which is claimed is shown in solid lines in the drawings. The uniform length dashed broken lines in the drawings illustrate environmental structure and form no part of the claimed design. The long dash-short dash broken lines in the drawings illustrate boundary lines identifying boundaries of the claimed design, wherein the long dash-short dash broken lines form no part of the claimed design. The broken uniform length broken lines indicate in determinant length/width/height and form no part of the claimed design.
